UNITED STATES PATENT OFFICE.

AUGUST KAMPF, OF MAGDEBURG, GERMANY, ASSIGNOR TO FRIED. KRUPP GRUSONWERK, OF SAME PLACE.

HYDRAULIC CONTROLLER FOR CARRIAGES HAVING AXIAL RECOIL.

SPECIFICATION forming part of Letters Patent No. 675,386, dated June 4, 1901.

Application filed August 25, 1896. Serial No. 603,905. (No model.)

To all whom it may concern:

Be it known that I, AUGUST KAMPF, a subject of the Emperor of Germany, and a resident of Magdeburg, in the Kingdom of Prussia, Germany, have invented certain new and useful Improvements in Hydraulic Controllers for Carriages Having Axial Recoil, of which the following is a specification.

The invention relates to those carriages in which the gun under the action of the shot recoils in the direction of its axis and wherein one or more hydraulic brakes regulate the rapidity and extent of this movement and at the same time serve to return the gun to its original or battery position and to hold it there until the next shot.

My invention relates to certain features of novelty, which will hereinafter be fully described, and particularly pointed out in the claims.

In the accompanying drawings, Figures 1, 2, 3, and 4 show the controlling parts in the positions which they occupy before the shot—that is, when in battery position—Fig. 1 being a longitudinal section through the controlling-valves on the line N O, Fig. 12; Fig. 2, a section on the line a b, Fig. 4; Fig. 3, a section on the line e f of Fig. 4, and Fig. 4 a section on the line g h of Fig. 2. Figs. 5, 6, 30 and 7 are views corresponding, respectively, to Figs. 1, 2, and 3, but showing the positions assumed by the several parts after a shot has been fired and recoil taken place and when the gun has been brought back into battery position by means of the brake-cylinder, Fig. 5 being a section on the line N O, Fig. 12. Fig. 8 shows the position of the main valve under the action of the shot; and Fig. 9 is a section on the line i k of Figs. 1 and 5, showing an arrangement, to be hereinafter described, which is only used for practice with the gun. Fig. 10 shows the parts of the improved controller assembled and in connection with the gun. Fig. 11 shows a section 45 through the brake-cylinder on the line l m, Fig. 10. Fig. 12 is a detail sectional view showing passage-way 26 and connections.

The check consists, essentially, of a main valve 1, the backflow-valve 2, the back-pressure check-valve 3, and the actuating-valves 4, 5, and 6, which are controlled by the lever

7. The housing 8, to which is bolted the housing containing the valves 4, 5, and 6, is mounted upon a fixed portion of the carriage and communicates with the brake-cylinder 55 12, which is secured to the carriage-frame through the medium of pipes 9 and 10. (See Fig. 10.) Pipes 9 and 10 are connected together by a turning box 11, secured to the pivot-block. The brake-cylinder 12 is provided on its inner surface in the usual manner with grooves 27 for the passage of the brake fluid, (see Fig. 11,) and the piston 13, which works in said cylinder, is secured to the sliding part of the carriage. Before the 60 shot is fired and when the gun is in battery position, as shown in Fig. 10, the parts of the controller take the positions shown in Figs. 1 to 4. Pipe 14 is at all times in communication with the accumulator, and the accumulator-pressure is constantly communicated through pipe 14, channel 15, around valve 6, through pipe 17, lifting the back-pressure check-valve 3, and beneath the main valve, which it keeps normally closed with 65 the assistance of the spring 18. The spring 2^a, working upon the backflow-valve 2, is strong enough to keep said valve seated against the accumulator. Likewise the accumulator presses upon the upper pistons of 70 valves 5 and 6, which are of somewhat greater section than the valve-seats, so that these valves, assisted by the springs working upon them, remain normally closed. The valve 28, Fig. 9, is normally left closed. Under 75 reaction of firing shot the recoil acting through the carriage, brake-piston, and cylinder forces the valves 1, 2, and 3 into the positions shown in Fig. 8, while the controlling-valves 4, 5, and 6 remain unmoved. 80 Since the pressure on the brake-piston induced by firing is greater than the pressure of the accumulator, it opens the valve 1 and the fluid escapes through the waste-pipe 19. At 85 the same time the valve 1 presses upon the fluid confined above the valve 3, and thereby closes said valve 3, so that the pressure cannot dissipate itself toward the accumulator. Through this impulse the pressure of the spring upon valve 2, Fig. 8, is also overcome, 90 so that said valve 2 opens and permits the fluid over the valve to pass through pipe 20

into channel 21, (see Fig. 1,) past valve 4 and through pipe 22, and eventually to the waste-pipe 19. As soon as the pressure of recoil is distributed through pipe 19 the parts again take the positions shown in Figs. 1 to 4.

To bring the gun back into battery position after a shot is delivered, the lever 7 is brought into the position shown in Figs. 5 and 6, at which time by reason of the arrangement of the lever projections 23, 24, and 25 and the relative lengths of the valve-rods it will follow that the rod of valve 4 will be released by projection 23, and valve 4 will be allowed to close before projections 24 or 25 reach the stems of valves 5 6 and open said valves 5 and 6, at which time communication between the chamber of valve 2 and the waste-pipe 19 is closed. A continued turning of lever 7 toward the left causes projection 24 to open valve 5, wherenpon the accumulator-pressure enters at once the channel 21 beneath valve 4 and reinforces the closing-spring of this valve. At the same time it passes through the pipe 20 into the chamber of valve 2 beneath the valve 1, at which time the entire section of valve 1 will be subject to the accumulator-pressure, since said pressure is already communicated to valve - chamber 3 through the pipe 17, which is in constant communication with the accumulator. Said valve 1 will therefore be held closed by a force corresponding to the accumulator-pressure applied to its entire cross-section in addition to its spring. A further movement of lever 7 causes projection 25 to come upon the stem of valve 6, which is shorter than the stem of valve 5, and open said valve 6. The accumulator-pressure now passes from pipe 14 directly past the valve 6 into the channel 26 through pipe 9, turning joint 11, and pipe 10 to the brake-cylinder 12. Since the rear wall of the brake-piston 13 is intentionally greater than the forward surface, the fluid which is passed back of the piston through the brake-cylinder channels 27 presses the piston forward, and inasmuch as this is connected with the upper part of the carriage shoves the same, together with the gun, back into the battery position. If the lever 7 is now moved to the right again, valve 6 first closes itself, whereby connection between the brake-cylinder and the accumulator is cut off. Then the valve 5 closes itself, whereby the pressure in the chamber of valve 2 is removed, so that the valve 1, which now stands only in communication with the accumulator-pressure through pipe 17, will only be loaded correspondingly to its under surface. The carriage and check are now in position for the next shot.

If the gun is to be allowed to slide back without firing, the lever 7 is left in its position and the valve 28, Fig. 9, is opened. The fluid expelled by the brake-piston then passes through channels 26, 29, and 30 direct into

the waste-pipe 19. The return to battery position follows, as heretofore.

Having thus described my invention, the following is what I claim as new therein and desire to secure by Letters Patent:

1. For use in connection with a recoil gun-carriage, having a brake-cylinder, adapted to take up recoil and return the gun; a fluid-pressure controller having fluid-passages for communication with the accumulator, for communication with the brake-cylinder, and for a waste-pipe of fluid under pressure of recoil; a main valve normally loaded by spring and fluid pressure to hold the brake-piston out, but yielding to pressure induced by recoil and permitting fluid to escape from the brake-cylinder to the waste-pipe passage; a backflow-valve located to permit escape of the fluid beneath the main valve at time of recoil, and a check-valve in the accumulator-pipe which closes at time of recoil, to cut off back pressure through said pipe, as explained.

2. In combination with a hydraulic controller having the brake-cylinder pipe, the accumulator-pressure pipe and the waste-pipe and having the main valve 1 normally holding the gun in battery position, but yielding to pressure induced by recoil; the valve 2 permitting escape of pressure from beneath valve 1; the check-valve 3 preventing back pressure in the accumulator-pressure pipe; a passage communicating between the chamber of valve 2 and the waste-pipe, and containing a valve 4; a passage between said valve-chamber and the accumulator-pipe; a passage between the brake-cylinder and accumulator and containing a valve 6; and a controlling-lever having projections located to open valve 4 by movement of the lever in one direction, and to permit the valve 4 to close and then successively open valves 5 and 6 by movement in the other direction; substantially as set forth.

3. In a hydraulic controller of the character described, a main valve in the waste-pipe, having a piston, a pipe normally communicating accumulator-pressure to a portion of the main valve's section, a passage normally closed by a valve 5 for communicating accumulator-pressure to the remainder of the main valve's section, a passage normally closed by a valve 6 for delivering the accumulator-pressure for running out the gun, and means for opening said valves 5 and 6 successively, whereby the main valve is first loaded against possibility of opening, and the pressure is then supplied for running out the gun, as explained.

In testimony whereof I have signed my name to this specification in the presence of two subscribing witnesses.

AUGUST KAMPF.
